CLAIM

The ornamental design for a fire protection sprinkler, as shown and described.

DESCRIPTION

FIG. 1 Is A Front Perspective View Showing a fire protection sprinkler In Accordance With A First Embodiment Of Our New Design;

FIG. 2 Is A Front View thereof;

FIG. 3 Is A Back View thereof;

FIG. 4 Is A Left Side View thereof;

FIG. 5 Is A Right Side View thereof;

FIG. 6 Is A Top View thereof;

FIG. 7 Is A Bottom View thereof.

FIG. 8 Is A Front Perspective View Showing a fire protection sprinkler In Accordance With A Second Embodiment of Our New Design;

FIG. 9 Is A Front View thereof;

FIG. 10 Is A Back View thereof;

FIG. 11 Is A Left Side View thereof;

FIG. 12 Is A Right Side View thereof;

FIG. 13 Is A Top View thereof; and,

FIG. 14 Is A Bottom View thereof.

(Continued)

The shading lines in the drawings show contour and are not intended to indicate surface ornamentation.

1 Claim, 12 Drawing Sheets
